UNITED STATES PATENT OFFICE

94,458

DESIGN FOR A STREET SIGN

Alfred C. Anderson, Fitchburg, Mass., assignor to William A. Hardy & Sons Co., Fitchburg, Mass., a corporation of Massachusetts

Application November 5, 1934, Serial No. 53,895

Term of patent 7 years

To all whom it may concern:

Be it known that I, Alfred C. Anderson, a citizen of the United States, residing at Fitchburg, in the county of Worcester and State of Massachusetts, have invented a new, original, and ornamental Design for a Street Sign, of which the following is a specification, reference being had to the accompanying drawing, forming part

Fig. 1 is a front view of a street sign, and
Fig. 2 is an edge view of a street sign showing my new design.

I claim:

The ornamental design for a street sign as shown.
